The ornamental design for a CD disk holder, as shown.

DESCRIPTION

FIG. 1 is a perspective view showing the front, top and left side of the CD disk holder;

FIG. 2 is a left side elevational view of the CD disk holder;

FIG. 3 is a top plan view of the CD disk holder;

FIG. 4 is a right side elevational view of the CD disk holder;

FIG. 5 is a bottom plan view of the CD disk holder;

FIG. 6 is a rear elevational view of the CD disk holder;

FIG. 7 is a front elevational view of the CD disk holder;

FIG. 8 is an enlarged sectional view taken on line 8 of FIG. 1; and,

FIG. 9 is an enlarged sectional view taken on line 9 of FIG. 2.

The broken line showing of environment is for illustrative purposes only and forms no part of the claimed design.
